[57] CLAIM

The ornamental design for a watercraft bottom hull, as shown and described.

DESCRIPTION

FIG. 1 is a bottom plan view of a watercraft bottom hull showing my new design;

FIG. 2 is a front elevational view thereof;

FIG. 3 is a rear elevational view thereof;

FIG. 4 is a longitudinal cross sectional view taken along line 4—4 in FIG. 1;

FIG. 5 is a cross sectional view taken along line 5—5 in FIG. 4;

FIG. 6 is a cross sectional view taken along line 6—6 in FIG. 4;

FIG. 7 is a cross sectional view taken along line 7—7 in FIG. 4;

FIG. 8 is a cross sectional view taken along line 8—8 in FIG. 4;

FIG. 9 is a cross sectional view taken along line 9—9 in FIG. 4; and,

FIG. 10 is a side elevational view thereof, the opposite side elevational view being a mirror image of that shown.

FIG. 1

FIG. 2

FIG. 3

FIG. 7

FIG. 8

FIG. 9

FIG. 10
